UNITED STATES PATENT OFFICE.

HENRY J. SCHMICK, OF LOCK HAVEN, PENNSYLVANIA.

LIFTING-JACK.

1,245,622.

Specification of Letters Patent.

Patented Nov. 6, 1917.

Application filed August 14, 1916. Serial No. 114,806.

To all whom it may concern:

Be it known that I, HENRY J. SCHMICK, a citizen of the United States, residing at Lock Haven, in the county of Clinton and State of Pennsylvania, have invented certain new and useful Improvements in Lifting-Jacks; and I do hereby declare the following to be a full, clear, and exact description of the invention, such as will enable others skilled in the art to which it appertains to make and use the same.

The invention relates to improvements in lifting jacks.

The primary object of the invention is to provide a device of the character mentioned, and one of a comparatively inexpensive and extremely simplified construction.

Another object of the invention is to provide a device of this character, and one in which maximum power is applied to the load to be lifted with a minimum amount of power for the operation of the same, and without sacrificing time, such as has not heretofore obtained in the art.

A further object of the invention is to provide a device of the character mentioned and one in which the weight of the load being raised is sustained at any desired point within the range of the same without resorting to the use of additional or extraneous mechanisms, such as pawls or the like, as has heretofore obtained in the known types of such devices.

With these and other objects in view, the invention relates to the certain new and useful construction as will be hereinafter more fully described, set forth in the appended claims, and illustrated in the accompanying drawings, in which:

Figure 1 is a front elevation of the device,

Fig. 2 is a side elevation,

Fig. 3 is a side elevation partly in section,

Fig. 4 is an elevation of the cam operating mechanism,

Fig. 5 is a horizontal transverse section on the line 5—5 of Fig. 4,

Fig. 6 is a plan view of the cam-gear and its actuating pinion as positioned on the inner wall of the removable face plate of the housing,

Fig. 7 is a fragmentary detail of the main drive gear.

Referring to the accompanying drawings, in which similar characters of reference designate corresponding parts in the several views thereof, the numeral 10 indicates a hollow standard, rising from a base plate 11, and having a housing 12 offset from the upper end thereof. Slidably mounted in the standard 10 is a lifting bar 13, which is formed with a foot portion 14 at its lower end, the same normally occupying a recess 15 formed in the upper face of the base plate 11, and a load supporting head 16 at its upper end.

The inner vertical face of the lifting bar is arranged in the form of a rack 17, which is co-extensive with the major portion of the same. Extending transversely of the housing 12, and journaled in the opposite side walls thereof, is a relatively heavy shaft 18 on which is secured a small spur gear 19 in meshed engagement with the rack face 17, of the lifting bar. Immediately adjacent the small gear 19 and secured to the shaft 18 is a toothed gear 20, the same being of relatively greater diameter than the first mentioned gear.

The housing 12 is provided with a removable side wall portion 21, in which is journaled one end of the shaft 18, and a removable front wall portion 22, by means of which the parts may be readily assembled or taken down when necessary. The removable side wall 21, of the housing, is formed with an offset front portion 23 for the purpose to be hereinafter set forth. The removable front wall 22, of the housing, is in the form of integral circular portions 24 and 25, the portion 25 being of less diameter than the portion 24, and both of the portions are formed with concentric bearing extensions 26 and 27, respectively.

Journaled in the bearing extension 26 is a stub shaft or spindle 28, which has its projected end 29 squared, as shown, and supports on its inner end a cam-gear 30, the periphery of the latter being toothed, as at 31, and in mesh with a small spur gear 32, which is formed with or secured on a

second stub shaft 33 journaled in the bearing extension 27. The outer or projected end 34, of the shaft 33, is squared in a manner similar to that of the projected end 29, 5 of the shaft or spindle 28, for the reception of a suitable operating crank or handle (not shown). With the crank or handle engaged on the squared end 29, of the cam-shaft 28, great rapidity with less power is obtained 10 in the operation of the lifting bar, and with the squared end 34, of the shaft 33, engaged and operated by the crank or handle, the speed of operation is reduced and the lifting power increased proportionately. This increase and decrease in speed of operation 15 and lifting power may be varied throughout a wide range by varying the ratio of the gear 32 with respect to the cam-gear, which ratio, in the present instance, is about 4 to 1. 20 The cam-gear 30 when properly positioned within the housing 12, is disposed in a vertical plane and at right angles to the gear 20, and has its inner face formed with a single radio-helical cam-member 35, adapted 25 to continually and progressively mesh with the radial curved teeth 36, of the gear 20. To effect the continuous engagement and progressive meshing of the working surfaces of the cam-element 35 with the radial teeth 30 of the gear 20, the said surfaces are disposed 30 on a curve of approximate cycloidal formation, and are made angular in transverse section in one direction of the element forwardly from the inner starting point 35 to a point approximately intermediate its length, and in a reverse angular or inclined relation for the remainder of its length to its outer end. This angularity of the cam-member or element 35, inclining first in one 40 direction and then in a direction opposite thereto, causes the member to support the weight on the jack at any point in the travel of the lifting bar 13 through the medium of the radial teeth 36, of the gear, in engagement 45 therewith, and dispenses with any and all of the usual clutch or stop mechanisms, heretofore provided for the purpose. The cam-member or element 35, as shown, is formed of a length to provide overlapping 50 ends, so that two of the radial teeth 36, of the gear 20, are in constant engagement, and the space between the overlapped ends of the member 35 is of just sufficient greater width than that of a single tooth 36 to allow 55 clearance of the same to and from engagement therewith, and in the revolution of the cam, the several teeth 36 are engaged consecutively.

To properly distinguish the approximate 60 cycloidal curvature of the cam-element 35, the same has been designated "radio-helical", since the motion defined by the travel of the member is radially or transaxially, and at right angles to the axis of the body 30,

and its direction of operation, in the present 65 instance, is clock-wise or right handed.

Having thus described the embodiment of the invention, it is to be thoroughly understood that various changes in the detailed construction and arrangement may be resorted to without departing from the spirit and scope of the same. 70

Having thus fully described the invention, what is claimed, is:—

1. In a lifting jack, the combination of a 75 standard, a lifting bar having a rack and moving vertically of said standard, a shaft journaled in the standard, a pinion mounted on the shaft and meshing with the rack, a revoluble member having a radio-helical cam 80 disposed on one face thereof, a gear wheel mounted on the shaft, the teeth of the gear being radial and engaging the radio-helical cam, the opposite faces of said teeth being similar and the opposite corners of the opposite faces of the teeth being disposed in alinement and parallel with a line drawn longitudinally through the axis of said gear wheel, the gear wheel being disposed at right angles to the revoluble member and one face 85 thereof being substantially in alinement with the axis of the revoluble member, whereby the cam engages the whole side surfaces of the teeth and exerts its force at right angles to the axis of the gear when rotating same. 90

2. In a lifting jack, the combination of a standard, a lifting bar having a rack and movably mounted in the standard, a shaft journaled in the standard, a gear wheel on the opposite end of the shaft, the teeth of the gear wheel being radially disposed, one surface of each tooth being concaved and the opposite surface being convex to form curved spaces between the teeth, a cam shaft square at one end and carrying a gear at the opposite end and mounted in the standard at right angles to the first mentioned shaft, the axis of the cam shaft being in substantial alinement with one face of the gear wheel on the first mentioned shaft, a radio-helical 100 cam projecting from one face of the gear on the cam shaft and meshing with the first mentioned gear, the walls of the cam being formed to engage the respective curved and convex surfaces of the teeth on the first 115 mentioned gear whenever the cam is in engagement, and the face of the cam being irregularly concave to engage the base of each curved space between the teeth when in meshing relation, a stub shaft square at one 120 end and carrying a pinion at its opposite end and mounted in the standard, the pinion meshing with the gear on the cam shaft.

3. In a lifting jack, the combination of a standard, a lifting bar having a rack and moving vertically of said standard, a shaft journaled in the standard, a pinion mounted on the shaft and meshing with the rack, a 125

revoluble member having a radio-helical cam disposed on one face thereof, the walls of the cam being formed to engage radial teeth of a gear wheel, a gear wheel mounted on the shaft, said gear wheel having radial teeth which engage with the cam, said gear wheel being disposed at right angles to the revoluble member, one face of the wheel be-

ing substantially in alinement with the axis of the revoluble member, whereby the cam ¹⁹ engages the teeth and exerts its force at right angles to the axis of the gear wheel when rotating same.

In testimony whereof I affix my signature.

HENRY J. SCHMICK.
